UNITED STATES PATENT OFFICE.

DANIEL L. BRAINE, OF NEW YORK, N. Y.

RAIL-CHECK.

1,238,386.

Specification of Letters Patent. Patented Aug. 28, 1917.

Application filed October 23, 1913. Serial No. 796,901.

To all whom it may concern:

Be it known that I, DANIEL L. BRAINE, a citizen of United States, residing at New York, in the county of New York and State 5 of New York, have invented certain new and useful Improvements in Rail-Checks, of which the following is a specification.

This invention relates to improvements in rail checks, and has for its object to provide an improved device to prevent "creeping" 10 of a rail after the same has been set in final position.

I am aware that many forms of devices have been constructed in the endeavor to 15 attain this object, but am not aware of any which accomplishes this purpose by utilizing an elliptical check provided with roughened surfaces which coact with the rail base as in the case of my device.

An advantage of my device is that I am 20 enabled to fit the same to individual spikes previous to their being driven and there is no danger of their being displaced thereafter. Furthermore, they operate automatically 25 and do not require adjustment from time to time. This and other objects will be set forth and shown in the following specification and accompanying drawings, in which;

Figure 1 is a side elevation of a spike showing my device applied thereto;

Fig. 2 is a horizontal section taken on the line 2 of Fig. 1;

Fig. 3 is a side elevation of my device as 35 applied to a driven spike;

Fig. 4 is a view along the line 4 of Fig. 3;

Fig. 5 is a transverse vertical section 40 through a rail and supporting means showing my device utilized in connection with a metal frame or tie-plate; and

Fig. 6 is a plan view of the same partially in section.

Like numerals refer to like elements throughout the drawings.

In the form shown in Figs. 1 and 2, 10 designates generally a rail having the flanged base 11 supported upon a tie 12. The screw spike 13 of conventional construction, is shown with the head 13^a there- 15 of retaining the rail base 11 in contact with the tie 12. My improved rail check is des- 20 ignated by numeral 15 and comprises an

approximately elliptical collar or plate apertured at 15^a to permit its fitting on the neck or shank of the spike 13 so as to freely 55 rotate upon the same. The periphery of the check 15 is roughened or sharply corrugated, as indicated by numeral 15^b. When the device is assembled, it is placed upon the spike and the latter is driven or screwed 60 to place, as shown in Figs. 1 and 2 with the minor axis at right angles to the longitudinal axis of the rail base, so that the portion of least diameter is in contact with the edge of the rail base 11. It will be apparent 65 that upon commencement of the "creeping" or longitudinal movement of the rail, the base being in contact with the roughened surface 15^b will cause a partial rotation of the check 15 so as to cause a wedge action to 70 ensue, due to the increasing diameter of the portion of the rail check between the spike 13 and the rail base 11. This wedge action serves to restrain the further "creeping" of the rail and consequently is caused automatically, as will be apparent upon initial 75 movement of the rail. Furthermore, the collar or check 15 being in contact with the surface of the tie or the like on both sides of the spike 13 will serve to resist or partially 80 resist over-turning or bending of the spike.

In the form shown in Figs. 3 and 4, my check is provided with an enlarged bore or aperture 15^c in which is fitted a bushing 16 of brass or the like, the same being provided with a square centrally located aperture 16^a to fit over and engage the driven spike 13'. It will be apparent that the action of the rail check is similar in this form to its action in the form shown in Figs. 1 90 and 2, the bushing 16 being held against rotation by the non-circular cross-section of the drive spike and the check proper being permitted to rotate upon said bushing.

In Figs. 5 and 6 I have shown a device 95 as applied to the form of rail supporting and fastening means wherein the rail is supported upon a block 20 and is held against lateral movement by a metal frame 21 supported upon the said block 20. This metal frame 21 is provided with the spiking slots or apertures 21^a and a flange or shoulder 21^b extends therearound. When screw spikes are utilized with this form of plate this

flange or shoulder 21^b may act as the reinforcement for the head of the spikes to prevent outward bending thereof, as shown in Fig. 5. This flange or shoulder 21^b is preferably of sufficient height to contact with the spike head when the latter is in holding position with respect to the rail so as to prevent cramping or binding of the check from possible contact with the underside 10 of the spike head. A rail check is carried upon one or more of these spikes, as shown in Fig. 6, wherein I have shown two diagonally opposed checks. The metal frame 21 is preferably extended outwardly of the 15 flanges or shoulders 21^b to contact with one side of the spike shank and at the same time it furnishes a seat for rail checks 15. The inner periphery of each shoulder or flange 21^b is spaced as clearly shown in Fig. 6 so 20 as to be slightly out of contact with the periphery of the check 15, the latter, however, being in contact with the rail base in its initial position as in the construction described and shown in Figs. 1 and 4. Partial 25 rotation of this rail check 15, however, will cause the same to engage the inner periphery of the shoulder or flange 21^b which receives the stress transmitted by the wedge action of the check 15 thereby relieving the 30 spike from the same. The portion of the metal frame around the spiking apertures designated by numeral 21^c extends partially around and preferably contacts with the body of the spike as clearly shown in Figs. 35 5 and 6 of the drawings, so that side stress received by the spike from the rail is transmitted to the metal frame and is thereby equally distributed between all spiking members.

40 It will be apparent that I have provided a new and simple form of rail check which will operate automatically upon initial "creeping" of the rail and which is easy to place in position and inexpensive to manufacture. It is obvious that my device is susceptible of many modifications and changes, and I do not wish to be restricted to the form shown and described, beyond the scope of the appended claims.

45 50 What I claim is:—

1. In combination, a spiking member, and a rail check rotatably mounted on said spiking member and adapted to coact with the plane surface of a rail.
2. In combination, a spiking member, and a rail-check having a curved corrugated surface adapted to engage the base of a rail, said rail check being rotatably mounted upon said spiking member.
3. In combination with a rail, a member adapted to restrain lateral movement in either direction of said rail, a spiking member arranged to secure said first named member to a tie, and a rail-check carried by 55 said spiking member and coacting with said

rail and first named member to prevent creeping of said rail.

4. In combination, a rail, a frame member adapted to restrain lateral movement of said rail, a rail check coacting with the lateral edge of the base of said rail and supported above said frame member to prevent "creeping" of said rail. 70

5. In combination, a rail, a frame member adapted to restrain lateral movement of said rail, a spiking member, a rail check carried by said spiking member and coacting with said rail and frame member to prevent "creeping" of said rail. 75

6. In combination, a rail, a frame member adapted to restrain lateral movement of said rail in either direction, a spiking member, and a rail check rotatably mounted on said spiking member and coacting with said rail and frame member to prevent "creep- 80 ing" of said rail. 85

7. In combination, a rail, a frame member adapted to restrain lateral movement of said rail, a spiking member, a rail check rotatably mounted on said spiking member, 90 said frame being provided with a shoulder portion, said rail check being arranged to coact with said rail and said shoulder to prevent "creeping" of said rail.

8. In combination, a rail, a frame adapted to restrain lateral movement of said rail, a spiking member, a rail check rotatably mounted on said spiking member adapted to coact with said frame and the base of said rail to prevent "creeping" of the latter. 95

9. A device of the class described comprising a collar, a rail-check rotatably mounted upon said collar and provided with a rail base engaging periphery. 100

10. A device of the class described, comprising a collar, a rail-check rotatably mounted upon said collar and provided with a rail base engaging periphery, said collar being apertured to permit driving there-through of a spike or the like. 105

11. A device of the class described comprising a collar, a rail-check rotatably mounted upon said collar and provided with a rail base engaging periphery, said collar being apertured to permit driving there-through of a spike or the like, the outer periphery of said rail-check being roughened or serrated to engage a rail. 115

12. In a device of the class described, a member having a spiking aperture therein, 120 a spiking member adapted to engage said aperture and having a head adapted to engage a rail base, a shoulder on said first named member for supporting the head of said spike on the side thereof opposite said rail and means mounted on said spike and engaging the rail to prevent creeping. 125

13. In a device of the class described, a member having a spiking aperture therein, 130 a spiking member adapted to engage said

aperture and having a head adapted to engage a rail base, a shoulder on said first named member for supporting the head of said spike on the side thereof opposite said 5 rail, and a rail check rotatably mounted with respect to said spike between the head of said spike and said first named member, the outer periphery of said rail check being

adapted to engage the edge of said rail base to prevent "creeping" thereof. 10

In testimony whereof, I have subscribed my name.

DANIEL L. BRAINE.
